CEMENT BASKET

William S. Althouse, Jr., Arcadia, Calif., assignor
to Baker Oil Tools, Inc., Vernon, Calif., a corporation of California

Application April 23, 1949, Serial No. 89,330

1 Claim. (Cl. 166—13)

1

The present invention relates to subsurface well tools, and more particularly to annular devices for forming a bridge between a casing, liner, or similar conduit string, and the wall of a surrounding enclosure, such as a bore-hole.

A device of the character indicated is disclosed in United States Patent No. 2,117,538. As shown in that patent, a cementing basket includes a plurality of leaf springs whose ends are welded to a supporting member. Each weld is in the form of a bead running around the end of each spring, being provided through use of an electric arc. The heat generated is of such high order as to nullify the desired spring-like characteristics of each spring at its welded end, about which the spring must flex, and induces spring failure at such end. In addition to the foregoing disadvantage, the welding operation is relatively time consuming and costly.

Accordingly, an object of the present invention is to provide a cementing basket which is not susceptible to spring failure.

A further object of the invention is to provide a cementing basket that can be produced in substantially lesser time and at substantially lesser cost.

Another object of the invention is to provide an improved cementing basket capable of being slidably mounted on a casing, liner, or similar conduit string.

Still a further object of the invention is to provide a cementing basket embodying welded-on leaf springs, in which the heat incident to the welding operation is not imparted to the bending areas of the springs, thereby enabling the springs to retain their spring-like characteristics in the regions where such characteristics are required.

This invention possesses many other advantages, and has other objects which may be made more clearly apparent from a consideration of several forms in which it may be embodied. Such forms are shown in the drawings accompanying and forming part of the present specification. These forms will now be described in detail, illustrating the general principles of the invention; but it is to be understood that such detailed description is not to be taken in a limiting sense, since the scope of the invention is best defined by the appended claim.

Referring to the drawings:

Figure 1 is a side elevation of a cementing basket mounted on a string of casing disposed in a well bore;

Fig. 2 is an enlarged view, partly sectional and partly elevational, of the lower portion of the device shown in Fig. 1;

2

Fig. 3 is an isometric projection of one of the leaf springs and flexible elements of which the cementing basket is formed;

Fig. 4 is a view similar to Fig. 2 of another embodiment of the invention;

Fig. 5 is a view similar to Fig. 2 of still another form of the invention.

As disclosed in the drawings, a basket A is mounted on a casing or liner section B forming part of a conduit string positioned in a well bore C. The basket is adapted to bridge the annular space D between the casing B and the wall of the well bore, and prevent cementitious and other materials E from moving through the annulus beyond the basket. The basket A is disclosed in the drawings as mounted on the casing B in an upright position. Accordingly, cementitious and other materials E will be prevented from moving downwardly through the annulus D below the basket.

The basket illustrated in Figs. 1 and 2 includes an inner ring or annular member 10 to which a plurality of circumferentially spaced leaf springs 11 are secured. These springs may be formed of flat flexible spring steel, or other suitable material, with their lower portions 12 secured, as by welding, to the exterior of the inner annular member 10.

The lower portion 12 of each leaf spring lies flush against the exterior of the ring 10. From this lower portion, the leaf spring tends to expand inherently outwardly, its intermediate portion 13 being inclined in a laterally outward and upward direction. The upper portion 14 of the leaf spring is inclined laterally inwardly and upwardly toward the casing B.

Of course, it is to be understood that the basket A may, in some applications, be mounted on the casing B in a reverse direction to that illustrated, in which event the intermediate portions 13 of the springs will be inclined laterally in a downward direction, with the ends 14 of the springs disposed inwardly in a downward direction toward the casing.

A basket element 15 extends along substantially the entire length of the intermediate portion 13 of each leaf spring 11, having one of its longitudinal marginal portions 16 secured to the inner face of the leaf spring 11, as by spot welding 17. This basket element 15 may be formed of relatively thin, flexible sheet brass, or other suitable material, and extends from the leaf spring to which it is attached circumferentially around the basket in overlapping relation with the inner surface of an adjacent flexible element 15 spot welded to an adjacent leaf spring 11. The

basket elements progressively overlap one another in the same manner and in the same direction around the entire circumference of the basket, in order to form a frusto-conical enclosure acting as an annular barrier between the casing B and the wall of the well bore C, or other confining enclosure.

Each flexible element 15 extends substantially from the ring or inner annular member 10 to the corner 18 where the leaf spring is bent to form the point of demarcation between its intermediate portion 13 and its upper portion 14. With this arrangement, the upper ends of the elements 15 are closely adjacent the wall of the well bore, with their lower ends closely adjacent the exterior of the inner annular member 10.

The flexible basket elements 15 overlap one another in slidable relation, forming, collectively, an imperforate basket.

The lower portion 12 of each spring 11 is secured to the inner ring 10 by spot welding. Such spot welding regions are provided at a plurality of longitudinally spaced points 19, 20, with the uppermost point 19 being disposed substantially below the terminus 21 of the intermediate portion 13 of the leaf spring. After the springs are all spot welded to the inner ring, an outer annular member or sleeve 22 is disposed over the ring 10 and the lower portions 12 of the springs. This outer annular member has a lower inwardly directed flange portion 23 snugly engaging the lower portion of the ring 10, and having an upper portion 24 snugly engaging the outer surfaces of the lower portions 12 of the springs. A shoulder 25 on the outer annular member 22 engages the lower terminals 26 of the springs, and thereby locates the upper end 27 of the outer sleeve at the lower end 21 of the intermediate spring portions 13, with the lower end 28 of the sleeve 22 preferably flush with the lower end 29 of the inner ring 10.

When properly disposed over the inner ring 10 and the lower portions 12 of the springs 11, the sleeve 22 may be secured to the inner ring 10, as by a plurality of circumferentially spaced spot welds 30, disposed below the spring members 11.

The assembled basket A may be placed over a casing section B, and may slide relatively thereupon by a limited longitudinal distance, determined by engagement of the inner ring 10 with upper and lower stop rings 31, 32 welded, or otherwise suitably secured, to the casing section B.

The casing section B, with the basket A mounted thereon, is lowered through the well bore C, which ordinarily has a lesser inside diameter than the maximum external diameter of the basket when unconfined. The spring elements 11 tend to expand outwardly inherently to enlarge the frusto-conical basket, and such spring elements are bent or flexed inwardly by the confining enclosure or well bore C when the basket is disposed within the latter. The springs bend around their portions 21 adjacent the upper end of the sleeve 24, moving laterally inwardly or outwardly. This lateral movement decreases or enlarges the effective size of the basket, the flexible basket elements 15 merely sliding circumferentially along one another.

During lowering of the casing string B in the well bore, the upper stop ring 31 engages the upper end of the inner ring 10, and pulls the basket A through the well bore C. In the event the casing string is elevated by a substantial amount, the lower ring 32 engages the lower end 29 of the inner annular member 10 and pushes the basket

upwardly, the bent heel portion 18 of each spring riding along the wall of the well bore without digging in.

If desired, the stop rings 31, 32 may be eliminated, and the basket A mounted on the casing section B by welding the inner ring 10 directly thereto.

The lower leaf spring portions 12 are secured to the inner ring by a spot welding operation, which is a comparatively rapid operation. The time of application of welding heat to each spring is extremely short, allowing little and insufficient time for the conducting of heat along the spring, which would tend to remove the temper from the spring element 11. It is to be noted that the uppermost spot weld 19 is spaced below the point 21 at which each spring flexes about the upper end of the outer sleeve 22. As a consequence, the heat applied to the upper spot welded region 19 during the relatively short welding period cannot pass to the flex point 21 of the leaf spring to the extent sufficient to elevate the temperature of the flexing region sufficiently high to remove its spring temper. Accordingly, the spring characteristics remain in each leaf spring 11, and it will not break at such point 21 despite its being subjected to repeated and extreme flexing during movement of the casing string and basket in the well bore.

Assurance is also had that the basket assembly will remain intact because of the support afforded by the outer sleeve 22, which embraces the lower portions 12 of the springs. As a matter of fact, the load on the springs 11 and their flexible elements 15, as due to the weight of cement E supported by the basket, is transmitted primarily to the outer sleeve 22, and from this sleeve to the inner sleeve 10. Only a small portion of the load is transmitted through the spot welds 19, 20 which, therefore, need not be very extensive and strong. Primarily, the spot welds 19, 20 serve to assemble the springs 11 around the sleeve 10, but the major portion of the load is transmitted from the springs 11 to the upper end of the outer sleeve 22 through the flex points 21 and from the lower ends 26 of the springs to the sleeve shoulder 25. The sleeve 22 is secured strongly to the inner ring 10 by spot welding 30 at points removed from the springs 11 themselves, thereby preventing this welding heat from adversely affecting the leaf springs.

In the form of invention disclosed in Fig. 4 the inner ring 10 is eliminated. The lower terminals 26 of the leaf springs 11 rest upon the sleeve shoulder 25, and the lower portions 12 of the springs are secured to the sleeve 22 by a plurality of spot welds 19a, 20a. As in the other form of the invention, the uppermost weld 19a is removed from the flexing point 21 of the leaf spring about the upper end of the sleeve 22, to prevent removal, or minimizing, of the spring-like characteristics from this member at this region. The basket device disclosed in Fig. 4 may be placed over a casing section B, with the lower portions 12 of the springs and the lower flange portion 23 of the sleeve engaging the exterior of the casing. The sleeve may then be suitably secured to the casing, as by the use of welding material 35a.

As in the other form of the invention, the major portion of the spring load is transmitted from the springs 11 directly to the sleeve 22, and from the sleeve to the casing through the weld 35. The spot welds 19a, 20a need not be made strong enough to carry the full load, which allows

lighter welds to be employed, such as spot welds.

In the form of invention disclosed in Fig. 5, the lower ends of the springs 12 are secured directly to a casing section or casing nipple F. Such mode of attachment is obtained by attaching the lower ends 40 of the springs directly to the nipple, by use of welding material 41. Such ends are comparatively remote from the point 21 about which the springs will flex. After the springs are welded to the nipple, a sleeve 22a is positioned over them in snug engagement with their lower portions 12 and with the sleeve shoulder 25a engaging the welds 41. This sleeve is then attached to the nipple F, as by use of welding material 42.

The major load on the springs 12 is transmitted directly from them to the encompassing sleeve 22a, and from the latter through the weld 42 to the casing nipple F. The springs will flex around the area of the upper end of the sleeve, which is remote from the lower ends 40 of the springs, where they are welded to the casing nipple. Heat is not conducted in sufficient quantity along the springs from the welding regions 40 to disturb the spring temper at the flex points 21.

The inventor claims:

In a cementing basket adapted to be mounted on a well conduit: an inner annular member to be placed on the well conduit; a plurality of circumferentially spaced leaf springs having their end portions disposed around the exterior of said inner member, said end portions lying flush against said member and the portions of said springs adjacent said end portions extending
